US00D379717S

United States Patent [19]**Apps et al.****Patent Number: Des. 379,717****Date of Patent: **Jun. 10, 1997**[54] **STACKABLE LOW DEPTH BOTTLE CASE**D. 327,972 7/1992 Apps et al.
D. 329,931 9/1992 Apps.[75] Inventors: **William P. Apps, Alpharetta; Gerald R. Koefelda, Atlanta, both of Ga.**

(List continued on next page.)

[73] Assignee: **Rehrig-Pacific Company, Inc., Los Angeles, Calif.****FOREIGN PATENT DOCUMENTS**247904 8/1962 Australia.
680197 10/1966 Belgium.[**] Term: **14 Years**

(List continued on next page.)

[21] Appl. No.: **34,317**[22] Filed: **Feb. 1, 1995****Related U.S. Application Data**

[63] Continuation-in-part of Ser. No. 919,376, Jul. 29, 1992.

Exhibits A & B: Two photos of an embodiment of U.S. Pat. No. 4,773,554 to Warwick.

[51] **LOC (6) Cl. 03-01**

Exhibits D-F: Three photos of a bottle neck resting type

[52] **U.S. Cl. D3/311; D3/313; D3/314; D3/341**

(List continued on next page.)

[58] **Field of Search** D3/304, 307-314; D9/424, 425, 341; 206/427, 429, 515, 519, 557, 562-564, 201; 220/509, 513, 514, 516, 517, 669, 670, 672, 673, DIG. 2, DIG. 12, DIG. 15**Primary Examiner**—B. J. Bullock

[57] The ornamental design for a stackable low depth bottle case, as shown and described.

DESCRIPTION

- D. 147,981 11/1947 Lehman.
 D. 152,907 3/1949 Richards D3/311
 D. 195,702 7/1963 Russo.
 D. 201,257 6/1965 Vidal.
 D. 255,097 5/1980 Carroll et al.
 D. 266,709 10/1982 Box.
 D. 284,841 7/1986 Rowland et al.
 D. 285,851 9/1986 Rehrig.
 D. 289,938 5/1987 Warwick.
 D. 291,178 8/1987 Toms.
 D. 304,123 10/1989 Warwick.
 D. 313,493 1/1991 Apps et al.
 D. 317,670 6/1991 Apps.
 D. 318,552 7/1991 Apps.
 D. 319,129 8/1991 Apps et al.
 D. 320,298 9/1991 Apps et al.
 D. 325,279 4/1992 Apps.
 D. 326,749 6/1992 Apps et al.
 D. 327,357 6/1992 Rehrig.

FIG. 1 is a top perspective view of a stackable low depth bottle case showing our new design;
 FIG. 2 is a bottom perspective view thereof;

FIG. 3 is a top plan view thereof;

FIG. 4 is a bottom plan thereof;

FIG. 5 is a side elevational view, both sides being identical;
 FIG. 6 is an end elevational view, both ends being identical;
 FIG. 7 is a cross-sectional view taken along line 7—7 of FIG. 3;

FIG. 8 is a cross-sectional view taken along line 8—8 of FIG. 3; and,

FIG. 9 is a perspective view illustrating the case partially loaded with bottles.

The broken line showing of bottles in FIG. 9 is merely for illustrational purposes and forms no part of the claimed design.
